CLAIM

The ornamental design for a tire for automobile, as shown and described.

DESCRIPTION

1. Tire for automobile

1.1 : Front

1.2 : Enlarged

1.3 : Enlarged

1.4 : Back

1.5 : Top

1.6 : Bottom

1.7 : Right

1.8 : Left

1.9 : End face view

1.10 : End face view

1.11 : Enlarged

1.12 : Enlarged

The broken lines shown in the drawings represent portions of a tire for automobile that form no part of the claimed design; fig. 1.1 is a front elevation view of the tire for automobile showing our new design; fig. 1.2 is a partial enlarged view of A-B portion of fig. 1.1; fig. 1.3 is a partial enlarged view of C-D portion of fig. 1.1; fig. 1.4 is a back elevation view thereof; fig. 1.5 is a top plan view thereof; fig. 1.6 is a bottom plan view thereof; fig. 1.7 is a right side elevation view thereof; fig. 1.8 is a left side elevation view thereof; fig. 1.9 is an end face view taken along line E-E of fig. 1.2; fig. 1.10 is an end face view taken along line F-F of fig. 1.3; fig. 1.11 is a partial enlarged view of G-G portion of fig. 1.9; and fig. 1.12 is a partial enlarged view of H-H portion of fig. 1.10.
